UNITED STATES PATENT OFFICE.

JOHN D. JAMES, OF PULASKI, VIRGINIA.

GRATE FOR ZINC-FURNACES.

SPECIFICATION forming part of Letters Patent No. 643,507, dated February 13, 1900.

Application filed September 11, 1899. Serial No. 730,146. (No model.)

To all whom it may concern:

Be it known that I, JOHN D. JAMES, of Pulaski, in the county of Pulaski and State of Virginia, have invented a new and useful Improvement in Grates for Zinc-Furnaces, of which the following is a specification.

In zinc-furnaces of the Belgian type there is a long narrow fire-box built of masonry having a set of elevated grate-bars, above which, in the fire-chamber, there is arranged a series of transversely-placed retorts, while below the grate-bars there is an ash-pit of a vertical depth sufficient to admit workmen, who every three hours or so are required to enter the ash-pits and with pokers or long iron tools break off the mass of clinkers adhering to the sides of the fire-box above the grate-bars, which clinkers rapidly form in the contracted portion of the furnace-chamber, which, on a level with the grate-bars in a zinc-furnace, is from ten to sixteen inches wide and from eight to twelve feet long. This work is performed while the fires are still burning. The clinkers are very hard, adhere with great tenacity to the sides of the furnace, and if not regularly removed at short intervals obstruct the fires and seriously affect the efficiency of the furnace. The clinkers are also difficult of access from below and the temperature in the ash-pit is ordinarily from 175° to 200°. As the workmen have to enter the space the work is not only very hard, but the effect of the heat upon the workmen is very severe.

My invention is designed to provide an improved form of grate-bar and method of operation which not only relieves the workmen from the influence of the heat, but also so changes the nature of the clinkers that they are no longer hard and vitreous, but are maintained as they are formed, in a spongy, frangible nature, that are easily disintegrated and removed; and to this end it consists of a grate of such construction as to be constantly fused on its upper surface with a rapidly-evaporating film or spray of water whose influence extends in the form of a vaporous spray to a lower stratum of coke and the clinker, whereby a great reduction of temperature is obtained and the clinkers changed in nature, as will be hereinafter more fully described.

In the drawings, Figure 1 is a vertical cross-

section of the lower part of a zinc-furnace. Fig. 2 is a horizontal section just above the grate-bars; and Figs. 3, 4, and 5 are front, side, and plan views, respectively, of a system of spray-pipes which form a part of the grate of the furnace.

In the drawings, Figs. 1 and 2, A represents the wall of masonry forming the lower part of the zinc-furnace. A' is the fire-box, about ten inches wide at the bottom and twenty inches wide at the top and about twelve feet long. At the bottom of this fire-box is a grate of special construction, and below it is a chamber A², forming the ash-pit, which is tall enough to admit the workmen who are required from time to time to clear off the clinkers above the grate. Now with such a proportion of fire-box having only a width of ten inches at the grate it will be seen that the mass of clinkers adhering to each side will soon obstruct the action of the fire.

My improved grate is formed as follows: At intervals of about four feet, more or less, there are cross-bars C C', whose ends are fixed in the masonry of the side walls. On the upper cross-bars the grate proper is laid, and the lower cross-bars C' are simply rests upon which the upper end of the workman's long bar is supported in slicing the fire and breaking off the clinkers.

As shown, the grate is formed of two longitudinally-arranged and solid grate-bars B³ B³, of square or other approved form of cross-section, and on either side adjacent to the walls and in parallel position are the iron pipes B B, one on each side and forming one of the grate-bars. These pipes are anchored down against displacement by long hook-bolts b, having hooks on their upper ends that embrace the iron pipes B at suitable intervals, and screw-nuts on their lower ends which engage with the lower cross-bars C'. The pipes B B are continuous or run into each other at their back ends, and at their front ends the inlet end is turned up at B' and is provided with a valve b', by which the admission of water is regulated, while the other section B connects with a waste-pipe or discharge-section B², controlled by a valve b². Throughout the length of the pipe-sections B B, that form grate-bars, there are

upon their upper surface numerous minute perforations forming jet-orifices a . When the zinc-furnace is in operation, the valve b' is opened and water is allowed to circulate 5 through the pipe B and to issue in jets directed upwardly, striking the lower layer of coke, and blackening the fire at the lower level and also spraying and falling back on both the solid grate-bars B^3 and the pipes 10 B themselves. The valve b^2 , which is practically closed, is left a little open, so that a little water will leak past the same and fall in a constant drip from the discharge-pipe B^2 . This is for the purpose of securing a circulation 15 through the whole pipe and for the important purpose of forming a telltale which shall indicate always that the grate-bar pipes B B in the furnace are full, for if there is any stoppage in the flow through these pipes 20 from any cause said pipes would quickly burn out. The issue of water from the jet-orifices is maintained constantly, but is not a forcible spray, except just before the time when the clinkers are to be cleaned out, when 25 the valve b' is opened full, and a forcible spray is then thrown upward into the lower level of the fire to still further cool it, so that the men may enter the ash-pit.

Now I am aware that it is not new to provide 30 hollow grate-bars with jet-orifices on their upper sides which direct a blast of air or steam into the fire to promote combustion, and, on the other hand, I am aware that in some forms of furnace a water-pipe has been placed 35 below the grate-bars with jet-orifices directed downward to sprinkle the floor of the ash-pit, and I do not claim any of these constructions or methods. My invention involves a distinctly 40 new principle in physics, and also very important and new results in the particular kind of furnace to which it is applied, as follows:

The cooling of grate-bars by air or by a body 45 of water circulating through them without issuing in jets acts only by conductivity and is very limited in extent. In my invention I take advantage of the rapid absorption of heat units involved in the change of a liquid to a gas which involves the principle of refrigeration 50 involved in the evaporation of a volatile liquid in an ice-machine. Thus when the grate becomes suffused on its upper side with water its rapid evaporation and conversion into vapor produces a far more rapid reduction 55 of temperature than the mere circulation of a body of water through an imperforate pipe could, and, furthermore, the lower stratum of coke becomes bathed in this vapor and becomes blackened, so as to still further 60 reduce the temperature. Not only is the heat thus greatly reduced and the work rendered more endurable to the workmen in cleaning out, but the clinkers themselves which accumulate and adhere to the walls 65 just above the grate-bars are entirely changed in their physical structure, so that instead of being dense, hard, and vitreous they are

spongy, friable, and easily disintegrated, and the severe labor of detaching them by hand is reduced to an unimportant and infrequent 70 requirement. As a further advantage of my invention it has been found that while the temperature of the ash-pit and grate is so much reduced there is no loss of heat in the furnace above, for the aqueous vapor in being 75 decomposed into its constituent gases in the furnace-chamber promotes the chemical union and intensifies the heat above, so as to give greater effectiveness to the fuel.

In carrying out my invention I do not limit 80 myself to the particular form of devices shown, as they may be changed in some respects without departing from my invention. Thus if the width of the fire-box should be made a little greater a third pipe B should properly 85 be placed in alternation with the solid grate-bars, whose longevity will thus be greatly increased.

One great advantage of my invention is the great saving in grate-bars. These as ordinarily 90 arranged rapidly burn out, involving in some zinc plants as great an expenditure as one hundred dollars a month for grate-bars alone. There is a great saving in fuel.

In describing my grate I show it in connection 95 with a zinc-furnace, in which it has especial values; but I would have it understood that I do not confine it to a zinc-furnace, but may apply it to any and all kinds of furnaces—such as boiler-furnaces, puddling-furnaces, roasters, calciners, and copper-furnaces burning ordinary fuel.

Having thus described my invention, what I claim as new, and desire to secure by Letters Patent, is—

1. A grate for a furnace having a portion of its bars formed of hollow water-pipes and provided with perforations on their upper sides discharging upwardly into the fire-box, and valves regulating the flow of water into and 110 discharge from said pipe, substantially as and for the purpose described.

2. A grate for a furnace having hollow grate-bars with perforations on the upper surfaces discharging into the fire-box, and means for 115 passing water through the same to form a constantly-suffused or superficially-overflowing film of water on the surfaces of the grate-bars to reduce their temperature by dissipating the heat units in surface evaporation substantially as and for the purpose described.

3. The combination with the zinc-furnace having a long and narrow fire-box and a deep ash-pit; of a grate interposed between the fire-box and ash-pit and consisting of cross-bars 125 supported at their ends by the walls of the furnace, and grate-bars arranged longitudinally on said cross-bars, part of said grate-bars being constructed in the form of hollow perforated water-pipes, and valves for controlling the flow of water therethrough substantially as and for the purpose described.

4. The combination with a zinc-furnace having a long and narrow fire-box, and a deep ash-

pit; of a grate consisting of two sets of cross-bars supported by walls of the furnace at their ends, a set of grate-bars arranged upon the upper set of cross-bars, part of which grate-bars are made of hollow perforated water-pipes and provided with valves for regulating the flow of water therethrough, and the lower set of cross-bars serving to support the cleaning-tools substantially as and for the purpose described.

5. The combination with a zinc-furnace having a long narrow fire-box and a deep ash-pit; of a grate consisting of two sets of cross-bars supported by the walls of the furnace at their ends, a set of grate-bars arranged upon the upper set of cross-bars, hollow perforated water-pipes arranged in the plane of the grate-bars, and hooked bolts hooking over said water-pipes, and anchored to the lower cross-

bars substantially as and for the purpose described.

6. The combination with a furnace-grate; of water-pipes arranged in the plane of the grate-bars between the grate-bars and side walls of the fire-box, said water-pipes having 25 perforations on their upper sides to discharge upwardly into the fire-box to reduce the clinkers, and valves for controlling the flow of water through said pipes substantially as and for the purpose described.

In testimony whereof I have signed my name to this specification in the presence of two subscribing witnesses.

JOHN D. JAMES.
